(57) **CLAIM**

The ornamental design for a myofascial release tool, as shown and described.

DESCRIPTION

FIG. 1 is a first perspective view of the myofascial release tool showing my new design;

FIG. 2 is a second perspective view thereof;

FIG. 3 is a third perspective view thereof;

FIG. 4 is a front elevation view thereof;

FIG. 5 is a top plan view thereof;

FIG. 6 is a rear elevation view thereof;

FIG. 7 is a bottom plan view thereof;

FIG. 8 is a right side view thereof; and,

FIG. 9 is a left side view thereof.

The broken lines in the drawings are for the purpose of illustrating portions of the myofascial release tool which form no part of the claimed design.

1 Claim, 6 Drawing Sheets(56)
